UNITED STATES PATENT OFFICE.

EMERY ANDREWS, OF KENNEBUNK, MAINE.

MILL-BOX.

SPECIFICATION forming part of Letters Patent No. 634,320, dated October 3, 1899.

Application filed April 22, 1897. Serial No. 633,264. (No model.)

To all whom it may concern:

Be it known that I, EMERY ANDREWS, a citizen of the United States, residing at Kennebunk, in the county of York and State of Maine, have invented certain new and useful Improvements in Mill-Boxes, of which the following is a specification, reference being had therein to the accompanying drawings.

Mill-boxes are used for various purposes, such as holding cops of yarn and rovings, as well as heavier articles, and are subject to hard usage in being dragged around when full and pushed or thrown aside when empty. The parts thereof are liable in consequence to wear through, to dent or bend out of shape, and to break. If the boxes must be sent off for repair, enough extra ones must be kept on hand to replace them temporarily, and a considerable expense is thereby incurred. It is the object of my invention to produce a light and rigid box of simple construction which shall present the most effective resistance at all points to wear or more violent damage and whose parts shall be capable of repair or replacement by workmen on the premises and with little expenditure of time and labor.

My invention will be described first with reference to the accompanying drawings, which represent the best embodiment thereof, of which I have yet contrived, after which its distinguishing characteristics will be pointed out and distinctly defined in the claims at the close of this specification.

In the drawings, Figure 1 is a vertical section of my mill-box at mid-length thereof. Fig. 2 is a view of the bottom of the same. Fig. 3 is a detail view showing one of the end blocks or plugs, which are described herein-after. Fig. 4 is a sectional detail.

The sides and bottom of the box are composed, preferably, of rectangular sheets 1 2 3 4 5 of leatheroid, although other suitable material may be used, leatheroid being satisfactory in use, since it is tough, smooth, and slightly flexible. At the eight edges in which these sides and bottom meet are placed strips 6 to 13 of the same material, these being L-shaped in cross-section and riveted to the said sides and bottom. Over each upper edge

of the box, is fitted a wooden rail 15 to 18, having a longitudinal slot therein to receive the said upper edge. These rails are riveted on, as at 19.

To each rail above described I apply a rail-cap of sheet metal, as 20 to 23. The said cap preferably is secured in place by rivets 19, which pass through the rail-cap as well as through the rail and the sides of the box, thereby securing the whole structure together. 55 The rail-cap is U-shaped in cross-section and formed with inwardly-bent edges, as 24 and 25. In some cases I form the rails 15 to 18 with narrow side grooves extending along the same, as at 26 27, Fig. 1, to receive the said 65 bent-in edges. In other cases, however, I omit the said side grooves, as shown in Fig. 4, the bent-in edges of the sides of the rail-cap bearing against the sides of the rail. In either case, whether the grooves be provided 70 or not, the bent-in edges of the rail-cap form close and tight joints with the sides of the rail and cracks or openings are prevented from existing.

28 to 31 are angle-pieces of heavy metal 75 cast of a shape to fit over the upper angles of the box and riveted through, as at 32. As will be apparent, the box has no rough or sharp edges which could either injure the hand in the handling of the box or tear the 80 cops of yarn or the like which are placed therein, smooth surfaces being presented at every point.

When loaded, the box frequently is dragged about in the roughest manner. I therefore 85 provide upon the bottom of the box wear-taking devices, such as now will be described.

40 40 are shoes extending longitudinally of the bottom of the box, preferably adjacent to the side edges thereof, and 50 is a shoe located 90 at an intermediate place on the bottom. The number and arrangement of the shoes of either kind employed on a box are optional. Each of the said shoes I connect with the box in a manner intended to facilitate the removal 95 thereof when worn and the application of a fresh one. Thus for each shoe to be mounted upon the box I attach to the latter a holder, the said holder and the shoe being constructed to permit of the detachable connection of the 100

shoe to the holder. The forms adopted in practice may vary. In the illustrated embodiment of the invention each of said shoes 40 40 consists of a sheet-metal shell, which 5 has laterally-extending projections or wings 41 42. In practice I introduce into the said shell a core of wood or other suitable material 39. When the core has been fitted into the shell or, as it may be termed, the "casing," 10 the core and casing are fastened together by one or more rivets 43. The shell or casing offers resistance to abrasion and is protected from collapsing or distortion by the core. The lateral wings of the casing serve as a 15 brace throughout its length against glancing blows received by the shoe. The holders which I have shown for securing the shoes 40 40 in place are designated 33, 34, 35, and 36. They are represented as located adjacent to 20 the four corners of the box. Each holder is held to the bottom of the box by one or more rivets 37, passing through the holder itself, the bottom of the box, and a portion of the lower angle-strip. The holders 33, 34, 35, and 25 36 are constructed to engage with the projections or wings 41 and 42 of the shoes 40. Each holder may consist of a strip of sheet metal, such as indicated at 35 in Fig. 2, and be applied in flat condition to the bottom of the 30 box, so that when the shoe is placed in position on the said strip the ends of the latter may be folded around the projections or wings of the shoe. The frictional hold of the said folded-over ends may be depended upon, if 35 desired, to hold the shoes in place. If desired, the ends of the strips composing the holders may be bent over into shape to clasp the wings or projections of the shoe prior to the application of the shoe to the holder or even of 40 the holder to the box, in which case the shoe will be applied to the holder by being slid endwise into the latter. Previously to applying the shoes to the bottom of the box the 45 spaces between the holders pertaining to each side edge of the box will be filled by an oblong sheet of leatheroid or other suitable material, as at 38 38, of the same thickness as the backs of the holders, and this sheet, with the said backs of the holders, will afford an even and 50 firm backing for the core and casing of the shoe. The core is made an inch or so shorter at each end than the casing, and into the empty ends of the casing I introduce the stems of two wear-receiving plugs 44 and 45, which are 55 made of steel or other suitable material, the said plugs having their exposed faces rounded and coming flush with the adjacent ends of the shoe, so as to leave no shoulder or exposed edges to injure the surface on which the box 60 is placed. In order to secure the plugs in place, a rivet or the like, as 401, is passed through the end of the shoe and the stem of the plug within the same. In order that the exposed face of the plug may come flush with 65 the end of the shoe, as aforesaid, the stem of the plug is smaller in diameter than the re-

maining part, and a shoulder 451 is produced. This shoulder bears against the outer edge of the holder adjacent thereto and holds the shoe from movement endwise.

In order, further, to arm the bottom of the box, I mount at its center and at such other point or points as may be deemed desirable a holder consisting of a cast frame, which in the drawings is shown as consisting of a flat 75 base or flange part 46, provided with rivet-holes, and a raised part 47, having somewhat the form of a truncated pyramid. The part 47 is provided with holes or slots 48 in its sloping sides. The precise shape of the frame 80 is of no importance. The frame will preferably be applied by first placing a strengthening-square of leatheroid on the bottom of the box, centering the frame thereon, and riveting the whole together by the rivets 49. Next 85 I place upon the summit of the sloping part 47 a wear-shoe 50, stamped out with four ears 51. These ears I bend over and into the slots 48, (one ear being shown in Fig. 2 as still extended,) whereby the shoe 50 is securely held 90 on the frame. The parts are to be so proportioned that the face of the shoe will come flush with the faces of the above-described shoes 40 40. When the shoe 50 becomes worn through, its ears readily may be straightened 95 out, thus freeing them from the slots 48, when it may be removed and replaced by a new one. If the casing of either shoe 40 40 wears through, it may be removed by unbending the bent-over ends of the holders 33 34, &c., 100 and immediately replaced, or the rivet 451 of one of the plugs may be driven out and the shoe withdrawn endwise from its holders.

I claim as my invention—

1. In a mill-box, the combination with the 105 box proper and a frame permanently affixed thereto, of a shoe provided with lugs and characterized by being detachably applied upon the said frame with the said lugs flexed or folded over thereon, whereby upon reverse 110 flexure of the lugs the shoe may be removed from the frame and a new one applied in like manner without detaching the frame from the box.

2. In a mill-box, the combination with the 115 box proper of one or more holders permanently secured to the same, and a shoe comprising a core contained in a wear-resisting casing with projections or wings and characterized by being removably applied to the said 120 holder or holders with portions of the latter flexed or folded over upon the said wings, whereby the shoe is frictionally secured to the holder or holders and may be removed therefrom by effecting reverse flexure of the 125 said portions thereof.

3. In a mill-box, the combination, with the walls of the box, and rails having side grooves and a bottom groove, the latter groove receiving the upper edge of the said walls, of 130 protecting rail-caps fitting over the top and sides of said rails and having its edges bent

inward and received in the said side grooves of the rails.

4. In a mill-box, the combination with the box proper, of holders applied thereto, a wear-resisting shoe inserted into said holders by being slid endwise therein, and a plug applied to the end of the said shoe and formed with a shoulder to engage the adjacent holder

and thereby retain the shoe from endwise movement, substantially as described. 10

In testimony whereof I affix my signature in presence of two witnesses.

EMERY ANDREWS.
